UNITED STATES PATENT OFFICE.

ERNST W. F. NATTER, OF EVERETT, MASSACHUSETTS.

BOTTLE-STOPPER.

SPECIFICATION forming part of Letters Patent No. 296,995, dated April 15, 1884.

Application filed January 3, 1884. (Model.)

To all whom it may concern:

Be it known that I, ERNST W. F. NATTER, of Everett, county of Middlesex, State of Massachusetts, have invented an Improvement in 5 Bottle-Stoppers, of which the following description, in connection with the accompanying drawings, is a specification, like letters on the drawings representing like parts.

This invention relates to means for stoppering bottles and securing the stopper in place over the mouth of the bottle and on its neck.

The invention consists, as hereinafter particularly set forth and claimed, of a cap having a rubber washer or plug loosely secured 15 in a hole in its crown to be jammed in the mouth of the bottle, inclined grooves in the inner face of the cap to engage lugs on the bottle-neck to move, by rotation of the cap, said cap toward or from the bottle-mouth, and an 20 annular internal projection in the cap to engage the washer or plug, to forcibly retain it seated, the cap so constructed being swiveled to the bottle-neck.

Figure 1 in vertical section shows the neck 25 of a bottle with my improved stopper applied thereto, the cap being in elevated position. Fig. 2 is a similar section, with the cap fully depressed to tightly close the bottle-neck. Fig. 3 represents the upper end or neck of 30 the bottle, with the cap entirely removed. Fig. 4 is a top view of the cap, and Fig. 5 is an under side view thereof.

The neck of the bottle A, near its upper end, has one or more projections, *a*, which are 35 adapted to enter notches *b*, (see Fig. 5,) formed in the interior of the cap B, the said notches *b* leading into grooves *b'*, (shown in dotted lines,) extended annularly about the interior of the said cap, the said grooves being inclined, 40 as clearly shown in Fig. 2, so that when the cap is rotated upon the neck of the bottle it will be forced downward or in the direction of the arrow 2, Fig. 1. The cap near its center is provided with a hole, *d*, through which 45 is extended the central part or neck, *e*, of an india-rubber plug or washer, *f*. The part *e* of the washer *f* has a head, *g*, which serves to retain the washer loosely in position in the cap B. At its inner side the cap is provided 50 with an annular rib or projection, *h*, which acts upon the upper side of the washer at a little distance back from its edge. The inside of the neck of the bottle is beveled, as at *i*, and the projection *h* is so arranged with re-

lation to the bevel *i* that as the cap is rotated 55 and forced downward from the position occupied in Fig. 1 to that in Fig. 2 the washer *f* will be forced down into the beveled mouth of the bottle, and the said washer will be pinched firmly between the inner side of the 60 bottle-mouth and the outer and lower portions of the said projection *h*, thus making a perfectly air-tight joint, and the washer, being loosely connected with the cap, does not rotate with the latter as the washer is being 65 forced into the bottle-neck.

The cap B has attached to it two bails, *m*, which in turn are pivoted upon a metal ring or wire, *n*, which is placed about the bottle-neck loosely, so that the said ring *n* may 70 rotate about the bottle-neck as the cap B is rotated, and may also slide upon the bottle-neck between the projections *o* and the collar *p*, extended outward from the said neck. The top of the cap is provided with two ribs, *w*, in 75 line with the grooves *b* in the cap, so that the position of the groove may be indicated from the outside of the cap, which is of advantage when the cap is being applied to the bottle-neck. 80

I am aware that grooved caps adapted to be engaged with projections on the bottle-neck are old, and such cap has contained india-rubber washers dropped therein; but in no such case has the washer been provided with 85 a neck and head and been forced down into the flaring open neck of the bottle, as herein shown.

I claim—

The bottle-neck provided with one or more 90 projections, *a*, and the metal cap B, provided with a central opening, and with an inclined annular groove, *b'*, and the annular projection *h*, combined with a flexible or india-rubber washer having a neck and head, the neck being extended through the cap, the washer being held loosely in the cap, and acted upon by the annular projection, the latter forcing the flanged part of the washer down into the neck of the bottle to close the same tightly, the cap 95 rotating independently of the washer, all substantially as described.

In testimony whereof I have signed my name to this specification in the presence of two subscribing witnesses.
